UNITED STATES PATENT OFFICE.

LUDWIG QUOSBARTH, OF NEW YORK, N. Y.

KNIFE.

SPECIFICATION forming part of Letters Patent No. 372,565, dated November 1, 1867.

Application filed April 28, 1867. Serial No. 236,470. (No model.)

To all whom it may concern:

Be it known that I, LUDWIG QUOSBARTH, a citizen of the United States, residing at New York, in the county and State of New York, 5 have invented new and useful Improvements in Knives, of which the following is a specification.

This invention has for its object to provide a knife-blade with a novel finger-guard; and to 10 such end it consists in the features of construction hereinafter described and claimed, reference being made to the accompanying drawings, in which—

Figure 1 represents a side elevation, partly 15 in section. Fig. 2 is a plan or top view when the finger-guard is in its forward position. Fig. 3 is a similar view when the finger guard is in its rear position.

Similar letters indicate corresponding parts. 20 In the drawings, the letter A indicates a knife-blade, and B is the knife-handle.

C is a finger-guard, which, as seen in Figs. 1 and 2, is adapted to rest over the back of the knife. The finger-guard is curved or cup-shaped, so that when in the position shown in 25 Fig. 1 a finger can be rested in the hollow of the finger-guard. The finger resting in said guard enables the operator to bring force to bear on the blade A, while at the same time 30 said finger is protected against coming into contact with the object which is being cut, or with chips from said article or object.

The cup-shaped guard C is provided with a short shank hinged to the knife-handle B by a transverse pivot-pin, D, and the said shank 35 projects beyond the pivot-pin to form a rounded tail-piece, D', which is acted on by the free end of a flat spring, E, arranged in a recess, E', in the handle and secured at one end by a screw, E', or otherwise. The free end of the flat 40 spring, acting on the end of the tail D', serves to confine the guard in place when turned over the knife-blade or when turned back over the knife-handle.

What I claim as new, and desire to secure 45 by Letters Patent, is—

A knife having a handle, B, provided with a recess, E', in combination with a flat spring, E, arranged in said recess, and a cup-shaped guard, C, having a shank hinged to the handle by a transverse pivot-pin, D, and having 50 the tail D', the end of which is acted on by the free end of the spring in the recess, said guard being adapted to swing over upon the knife-blade and back over the knife-handle, sub- 55 stantially as described.

In testimony whereof I have hereunto set my hand and seal in the presence of two subscribing witnesses.

LUDWIG QUOSBARTH. [L. S.]
